UNITED STATES PATENT OFFICE.

OSCAR H. FAIRCHILD, OF DENVER, COLORADO, ASSIGNOR OF TWO-THIRDS TO WILLIAM ARCHER DIBOLL, OF DENVER, COLORADO.

AUTOMATICALLY-OPERATED FILTER.

No. 884,914.

Specification of Letters Patent. Patented April 14, 1908.

Application filed August 13, 1907. Serial No. 388,375.

To all whom it may concern:

Be it known that I, OSCAR H. FAIRCHILD, a citizen of the United States of America, residing at the city and county of Denver and State of Colorado, have invented a new and useful Automatically-Operated Filter, of which the following is a specification.

My invention relates to improvements in automatically operating filters; and the objects of my invention are: First, to provide a revolving multiple and duplex unit automatically operating filter. Second, to provide a multiple and duplex unit revoluble and automatic sand-cake discharging filter. Third, to provide a simple, durable, and economically operating revoluble filter, in which the filters are divided into duplex groups that are connected together in series to a common suction pipe, and in which all of the suction pipes are connected to a central suction mechanism, and that is operated automatically and intermittently to filter slime ore-pulp solutions for a predetermined portion of its revolution, and that expels and discharges the resulting sand-cake during a predetermined part of the remainder of its revolution. I attain these objects by the mechanism illustrated in the accompanying drawings, in which:

Figure 1, is a side elevation of my improved filter. Fig. 2, is a vertical sectional view thereof taken longitudinally through the supporting shaft of the filter. Fig. 3, is a plan view of one of the boards to which the filters are secured, showing the arrangement of the pipes which form the framework of the filter. Fig. 4, is a front view thereof. Fig. 5, is a sectional view of one of the filters, on the line 5—5 of Fig. 4. Fig. 6, is an end view of one of the shaft sections. Fig. 7, is a side view of one of the discharge hoppers, showing one of the semi-circular plates secured thereto, having the pins which operate the valves which open and close communication with a source of fluid under pressure. Fig. 8, is a view of the opposite plate, showing the pins which operate a set of valves which open and close communication with a vacuum tank. And Fig. 9, is a sectional view of one of the valves.

Similar reference numerals refer to similar parts throughout the several views.

Referring to the drawings, the numeral 1, designates a semi-circular receptacle or tank 5 of suitable width, which is preferably con-

structed of tongue and groove boards, and which is adapted to hold a cyanid or other chemical ore-pulp solution or a solution of any kind that requires filtering to separate the solution as clear, clean, liquid, from the ore-sand or other material mixed with it. This tank is supported by upper and lower rectangular frames 2 and 3, respectively, which are connected by vertical and oblique bracing timbers as shown. Within the tank is rotatably mounted a wheel 4, comprising the rim 5, spokes 6, hub 7, and shaft 8; the rim 5 I term the spokes rim. The rim and spokes are preferably cast integral and the hub is made in two parts, with flanges 5^a that are bolted to a central disk portion 6^a by bolts 7^a; this disk portion 6^a forms an integral part of and unites the inner ends of the spokes. The shaft is cast integral with the two hub portions, and when they are secured the spokes project from opposite sides of the hub of the wheel, and the wheel then forms an integral structure. The ends of the shaft 8, are journaled in boxes 9, secured upon the frame 2. The hub 7, is formed with axial chambers 10 and 11, which are separated from each other by partition plates 1, 2 which fit into counterbores formed in the face of the half hubs, and axial bores 13 and 14 extend from these chambers to the outer ends of the shaft. A plurality of threaded holes extend radially from the chambers 10 and 11, through the periphery of the hub, and in these holes are screwed short sections of pipe 15. At the base of each spoke, and projecting laterally from opposite sides thereof, are nipples or short sections of pipe 16, which are screwed into openings in the spokes, and have elbows 16^a, which receive short sections of pipe 16^b. The pipes 16^b on one side of the wheel are screwed into plug valves 16^c, while those on the opposite side connect with similar valves 16^d. The spokes are hollow from end to end to form passageways from the nipples 16 out through the rim of the wheel, and into the opposite end of each plug valve is screwed a short section of pipe 17, the free end of which is connected to the free end of the adjacent pipe 15, by a union 18. Thus, each spoke is connected with the hub chambers 10 and 11, through the two valves 16^c and 16^d and their pipes.

All of the valves 16^c on one side of the several spokes, are provided with suitable plugs or stems 19, which open or close communi-

cation between the spokes and the hub chamber 10, while the valves 16^p on the opposite sides of the spokes are provided with similar plugs or stems 20, which open or close communication between the spokes and the hub chamber 11. The plugs 19 and 20 have ports 21, which extend transversely through them, so that when turned to a certain position in the valves they either close or open communication between the spokes and hub chambers.

The plugs are each provided with a squared end 22, which extends out beyond the valve, and upon these squared ends bell crank arms 23 are secured, which are adapted to engage a pair of pins, as the wheel revolves, to first close the valve and then open it at a predetermined point in the wheel's movement. The pins 24 and 25 which operate the valves 16^c, are secured in a segmental bracket 26, which is attached to the rear side of a hopper to be presently described, and extend in adjacent to the bell crank arms so that the pins will stand in the path of said arms; and the pins 27 and 28, which operate the valves 16^p, are secured in a similar bracket 29, and these brackets may be provided with a plurality of holes, so that the positions of the pins may be changed to operate the valves at different predetermined points in the movement of the wheel.

The rim of spokes is made somewhat wider than the spokes, and upon it is mounted a felly portion 30, of wood, and upon this felly portion there is secured a wide peripheral rim portion 31, which I term the felly rim, and which is also preferably constructed of wood. This felly rim portion 31, projects from the center of the felly portion 30, an equal distance on each side of it, the distance depending on the capacity or suction area of the filters to be used on the wheel. The filter wheels may be made from about four feet to eight or more feet in diameter, and the outer rim portion 31 would vary from about eighteen inches to about two or more feet on each side of the center of the felly, or from about three to eight feet wide. This felly portion comprises blocks of wood which are secured to the top of the cast rim of the spokes of the wheels 4, and the felly rim is preferably constructed of wooden planks laid crosswise across the felly blocks, and each felly rim plank is secured thereto independently of the others by bolts or other suitable means. These rim planks I term rim sections. Each felly block is curved on its inside edge to fit the curvature of the cast rim of the wheel 4, but its outside edge is made flat; consequently the felly rim sections 31 lie flat on top of them and are flat on top. To the under side of each of these rim sections, I secure a plurality of filters, which in general I will number 33; these filters comprise in particular a yoke-shaped piece of pipe 34, the

free ends of which extend up through apertures in the rim section and are secured thereto both above and below the rim plank by check nuts 35, washers 36 being placed between the check nuts and the rim section. The depending yoke-shaped portion of this pipe is perforated along its length with numerous small holes, which extend through its shell into its interior aperture. Over this perforated pipe I place a rectangular shaped narrow bag or sack 37, of any suitable filtering material, preferably canvas, which is formed to fit loosely over the yoke-shaped pipe. Inside of each canvas bag a wire screen of any suitable mesh is placed, and around the wire screen within the bag a sheet of cocoa-matting 40 is folded to surround the screen, and the matting and screen are placed in the bag to rest on the pipe between its ends, and the screen and matting and bag are sewed together at intervals throughout their area by stitches of thread. The filters are thus secured rigidly to the inner side of the rim sections, and project radially from them towards the axial center of the shaft of the filter wheel.

The upper edges of the open ends of the bags are secured to the under side of the felly rim sections, by being laid up against the under side of the rim planks and fastened there by strips or cleats 42, preferably of wood, which are secured to the under side of the rim sections by nails or screws. The edges of each bag are given a coat or two of tar or a suitable water-proof paint, to make a tight joint between the canvas bags and its rim plank. I preferably place five of these filters on the under side of each rim section throughout the circumference of the filter wheels, and arrange them also on both sides of the spokes of the wheel; consequently two circumferential rows of filters are formed on each filter wheel, and they are placed at equal distances on opposite sides of the circumferential center of the cast rim and spokes and hub of the filter wheel. To the outside end, or the end of the yoke-shaped pipe of each filter that is farthest from the center of the wheel, I secure a cap 43, which closes the entrance to that end of the pipe, and to the inside end of these yoke-shaped pipes I connect the end of a nipple elbow 44. To the nipple portion of this elbow, I connect one end of a short piece of rubber hose 45, which with the nipple elbow is pointed towards the outside edge of the rim plank a short distance, and I secure the opposite end of this short piece of hose to the nipple end of a tee pipe fitting 46. I preferably arrange these two circular rows of filters in groups of five filters each, and I place two groups of five filters each opposite each other, on opposite sides of the spokes, and in line with the spaces between each pair of the spokes of the cast filter rim, and I secure these two groups of

95

100

105

110

115

120

125

130

five filters each to the under side of each rim section. There is consequently between the center of each pair of spokes and extending across the under side of each rim section of the filter wheel in axial alignment with each other, two groups of five filters each, and these two groups of each rim section I term a filter set, and as there are fourteen spokes illustrated and fourteen rim sections, there 10 are fourteen filter sets in the circumference of the wheel, and each filter set contains ten filters, which are divided into two groups of five filters each.

The filters of each filter set are connected 15 to one of the hollow spokes of the filter wheel, and if desired each filter of each group of each filter set may be connected directly to either one of the adjacent hollow spokes, but I preferably connect the five filters of each group 20 of filters together to a line pipe 47, and then connect the line pipe of each group by means of a tube 48 connected to one end of each line pipe and also connected to a tee 49, which is connected to a nipple 50, that extends 25 through the rim section and the felly blocks and cast rim of the filter wheel, into the hollow spokes. To effect this arrangement of the filters I secure one end of each felly block and one side edge of each rim section far 30 enough over the top end of a spoke to extend the nipple 50 down through the rim section and felly blocks and thread it into a threaded aperture in the cast rim of the filter wheel that connects with the aperture in the spoke. 35 The five filters of each group are secured at a few inches apart to the under side of each rim section, and all of these filters are made alike and are secured to the rim planks in the same manner, and the outer ends of their 40 pipes are closed by caps 43, and their inner ends are provided with the nipple elbows 44, and short rubber pieces of hose 45, to the end of which tees 46, are connected, and the line pipe that connects these four filters of each 45 group consists of enough nipples, to connect all of the tees 46 of the five filters of each group, and to connect to the rubber tube 48 which connects with the tee 49 of the nipple 50 that connects with the aperture in the hollow spoke of each rim section; consequently 50 each set of two groups of five filters is connected by a line pipe with one spoke of the filter wheel, and with an air suction mechanism connected with the hub and axial shaft 55 of the filter wheel, and also with an air pressure mechanism, and these are controlled by the valve mechanism of the hub of the filter wheel. In the tank I place two ore sand cake catching and discharging hoppers 53, 60 placing one on one side of the filter wheel in the tank, and the other on the opposite side. These hoppers are positioned centrally over the filter shaft directly under the circumferential row of groups of filters on its respective side of the filter wheel, and are supported

there by suitable braces, which are secured to the hoppers and to the sides of the tank, and each hopper is provided with discharge chutes 55, which are arranged to straddle the shaft by being bifurcated into two spout portions which extend from the bottom of the hopper and pass down on opposite sides of the shaft, and out through apertures formed in the opposite sides of the tank beyond which they extend far enough to connect 70 with a conveyer adapted to convey the ore sand cake away from the filtering machine. 75

In the end of the bore 13 of the shaft 8, is inserted one end of a pipe 54, the other end of which enters a suitable vacuum tank 55, 80 which is provided with an outlet pipe 56, and with a pipe 57, leading to a suitable vacuum pump, not shown. A stuffing box 58, in the end of the shaft 8, surrounds the pipe 54, and prevents the ingress of air, as the shaft revolves around the pipe. At the opposite end of the shaft, a pipe 59 is inserted, passing through a stuffing box 60, similar to the box 58, and this pipe connects with a source of steam or of air under pressure. To this end 85 of the shaft is keyed a sprocket wheel 61, which connects with a sprocket wheel 62, on a drive shaft 63, on the other end of which is a belt pulley 64, which is connected with a source of power. The chutes are adapted to 90 catch and discharge the cakes composed of fine ore sand which are deposited upon the filters, as the solution is drawn through them, and which are thrown off at a predetermined time by the admission into the filters of 95 steam or of air under pressure, as will presently be more fully explained.

The operation of the improved filter is as follows: The tank 1, is supplied with cyanid or other chemical ore-pulp solution from a 105 source of supply, and the filter-wheel is caused to revolve slowly so that the depending groups of filters as they pass successively into the solution are submerged therein for a period of time sufficient to permit them to be filled with solution. Meanwhile, a vacuum is created in the vacuum tank causing a strong suction through the bore or passage 13, chamber 10, and hollow spokes to the filters, which are wholly or partially submerged, all 110 the valves communicating with which filters being open. Now, as each spoke approaches and rises beyond a horizontal position, the solution will be drawn from the filters of its respective groups of filters through the spoke valve 16^c, chamber 10, passage 13, and pipe 54 to the vacuum tank 55, the valve 16^b on the opposite side of the spoke being closed during this period, and as the spokes communicate with the line pipes of the groups of filters, each group of filters will be thoroughly drained before entering the solution again. Shortly after each group of filters passes out 115 of the solution and the solution is drawn out of them by the air suction, the bell crank arm 120 125 130

23, on the stem of their controlling valve 16^c, contacts with the trip pin 24, by which the valve is given a quarter turn, and closes communication between the filters and the vacuum tank. As the filters pass on and over the upper ends of the hoppers 53, the bell crank arm on the stem of the valve 16^b, contacts with the trip pin 27, by which the valve is opened, and a supply of steam or air under pressure is admitted to the spokes and through them to their respective group of filters, and the cakes of fine ore-sand and mud which have been caused to adhere to the outside surface of the canvas bags of the filters during their passage through the solution, by the vacuum, are thrown off, and fall into the hopper 53, from which they slide through the chute portion of the hopper to the outside of the tank. The valve is soon reversed or closed, by contact 20 with the pin 28, and as the groups of filters or a set of filters again enter the solution, the valve 16^c is again opened by contact of its bell crank with pin 25, and the former operation is repeated.

25 My improved filter is well adapted to the treatment of slimes, which frequently carry a high percentage of value. The solution, after passing through the filters, is clear and clean and subsequently undergoes suitable treatment for the recovery of the values which are in it; one form of treatment being to pour the solution into a receptacle containing zinc shavings, upon which the gold in the solution is precipitated, the mass being then subjected to heat, causing the gold to form in a button, while the zinc passes off in fumes.

The wheel may be revolved at any practicable degree of speed, and the trip pins for the valves may be set to open and close the valves at any predetermined time. Thus, the filter is automatic in its operation and only requires that the solution in the tank shall be maintained at a level at about the axial center of the shaft in order to give satisfactory results.

Having described my invention, what I claim as new and desire to secure by Letters Patent, is:

50 1. A revoluble filter, comprising a tank; a wheel mounted in said tank having passages which connect on one side with a vacuum tank, and on the other side with a source of fluid under pressure; filters on said wheel communicating with said passages; and means for controlling said passages.

2. A revoluble filter, comprising a solution tank; a wheel mounted in said tank having a wide felly rim, said wheel and rim being arranged so as to be partially submerged and having passages which connect on one side with a vacuum tank and on the other side with a source of fluid under pressure; filters connected to the under side of said rim por-

tion communicating with said passages, and valves for controlling said passages.

3. A revoluble filter, comprising a semi-circular solution tank; a wheel mounted in said tank so as to be partially submerged, and having passages which connect on one side with a vacuum tank and on the other side with a source of fluid under pressure; a circumferential row of groups of filters on said wheel communicating with said passages, and automatically operated valves for controlling said passages.

4. A revoluble filter, comprising a solution tank; a wheel mounted in said tank so as to be partially submerged, and having hollow spokes communicating with passages in the shaft of said wheel; a laterally projecting rim on said wheel communicating with said hollow spokes; a group of filters radiating from said rim connected to each hollow spoke, the filters of each group being connected to a common pipe that leads to a hollow spoke; a pipe in one end of said shaft leading to a vacuum tank; a pipe in the other end of said shaft leading to a source of fluid under pressure; and automatically operated valves for controlling communication between said spokes and shaft.

5. In a revoluble filter, the combination with a solution tank, of a wheel mounted therein so as to be partially submerged, having a hollow shaft, and hollow spokes communicating therewith, one end of said shaft being connected with a vacuum tank, while the other end is connected with a source of fluid under pressure; filter bags on said wheel communicating with said hollow spokes, and valves which are automatically operated as the wheel revolves, to open or close communication between the hollow spokes and shaft at any predetermined point in the travel of the wheel.

6. In a revoluble filter, the combination with a semi-circular solution tank, of a wheel mounted therein, having hollow spokes communicating with a hollow shaft and automatically operated valves for controlling communication between the spokes and shaft; filtering bags on said wheel communicating with the hollow spokes; a pipe in one end of the shaft connecting with a vacuum tank; a pipe in the other end of the shaft connecting with a source of fluid under pressure, a partition in said hollow shaft forming independent passages on each side of its center, and a power-driven wheel on one end of said shaft.

7. In a revoluble filter, the combination with a solution tank, of a wheel mounted thereon provided with rim projecting laterally from its circumferential plane and arranged to be partially submerged in said tank, said wheel being provided with a shaft provided with independent axial passages

- extending from each end and separated by a central partition, and hollow spokes connecting at their lower ends with the independent passages in the shaft; automatically operated valves on each side of the spokes at their lower ends, which control communication between the spokes and the separate shaft passages; pipes in the ends of the shaft, connecting respectively with a vacuum tank 10 and a source of fluid under pressure; filtering bags radially arranged on said rim at the extremities of the spokes and having pipe connection with said spokes; a sprocket wheel on one end of said shaft connected by a chain 15 with a power-driven shaft mounted on said tank, a sprocket wheel on said power shaft, and a sprocket chain belt mounted on and connecting said sprocket wheels.
8. In a revoluble filter, the combination 20 with a solution tank, of a wheel having a rim portion mounted therein so as to be partially submerged, said wheel being provided with a shaft formed with an axial passage extending from each end, separated centrally of the 25 shaft by a partition, means including pipes for connecting the lower ends of said hollow spokes with the separate shaft passages, valves at the lower end of each spoke, filter bags depending from said rim and connected 30 by pipes to said hollow spokes, hoppers beneath the uppermost filter bags provided with discharging chute portions extending out of said tank; pipes in the ends of the shaft, which lead respectively to a vacuum 35 tank and a source of fluid under pressure, and means for automatically opening and closing the valves at any predetermined point in the rotative movement of the wheel.
9. In a revoluble filter, the combination 40 with a solution tank, of a wheel mounted therein provided with hollow spokes and a broad rim, said wheel having a shaft provided with axial passages separated by a central partition, means including valve-controlled 45 pipes for connecting said hollow spokes to said shaft's axial passages; pipes in the ends of said shaft leading respectively to a vacuum tank and to a source of fluid under pressure; a circumferential row of groups of filtering 50 bags secured to said wheel, means including piping for connecting said groups of filtering bags to said hollow spokes, a hopper under the uppermost groups of filter bags arranged to discharge without the tank, said hollow 55 spoke and shaft passages being connected by valve controlled piping, said valves being provided with projecting stems terminating in bell crank arms, and pins arranged in the path of said bell crank arms, by which said 60 valves are opened and closed at predetermined points in the rotary movement of the filter.
10. In a revoluble filter, the combination 65 with a solution tank, of a wheel mounted therein, having hollow spokes, and a wide peripheral rim extending laterally on opposite sides of said wheel, a shaft having an axial passage extending in from each end to independent hub chambers divided by a partition, one of said passages being connected with a 70 vacuum tank, while the other is connected with a source of fluid under pressure, valves and pipes connecting said hollow spokes and hub chambers, cylindrical plugs in said valves which control communication between the spokes and shaft, having projecting stems terminating in bell crank arms, pins arranged in the path of said arms for operating the valves, and filtering bags secured to the inner surface of said rim and arranged to project radially from said rim towards the axial center of said wheel's shaft, and piping arranged to connect said filtering bags with 75 said hollow spokes.
11. In a revoluble filter, the combination 80 with a solution tank of a wheel mounted to stand partially within said tank, having a pair of axial chambers in its hub separated by a partition, and passages extending from said chambers to the ends of a supporting shaft, one of which connects with a vacuum tank and the other with a source of fluid under pressure, said chambers being provided with radial holes extending through the hub; hollow spokes having valves connected with 85 opposite sides of their lower ends; pipes extending from the radial holes of the hub chambers and connected with the valves; plugs in said valves for controlling communication between the hollow spokes and chambers, having projecting stems terminating in bell crank arms, pins adjustably secured in brackets for operating the valves at predetermined points in the wheel's movement; filtering bags arranged transversely across 90 the rim of the wheel in groups, the filtering bags of each group of filters being connected together and a pipe communicating with the connection of filtering bags and said hollow spokes, and a hopper on each side of the 95 wheel extended adjacent to the under side of the uppermost group of filtering bags and arranged to discharge without the tank.
12. In a revolving filter, the combination 100 with a solution tank, of a wheel having hollow spokes communicating with independent axial passages in a supporting shaft, one of which is arranged to connect with a vacuum tank and the other with a source of fluid under pressure; a plurality of filtering bags connected together by pipe connections into groups of filtering bags secured to the opposite sides of the inner peripheral side of the 105 rim of said wheel, a line pipe arranged to connect each group of filtering bags with said 110 hollow spokes, and valves automatically operated at predetermined points in the travel 115 of the wheel, for opening or closing communication between the spokes and shaft passage.

13. In a revoluble filter, the combination with a wheel, comprising a shaft having independent axial passages terminating in chambers which are separated by a partition, 5 said passages connecting respectively with a vacuum tank, and a source of fluid under pressure, said wheel having hollow spokes provided with a rim; felly blocks secured to spokes, a circumferential row of flat independent rim sections secured to said rim blocks, and extending laterally across said rim blocks and beyond them far enough to support on opposite sides of said wheel a circumferential row of filtering bags, said filtering 10 bags being arranged in groups on each rim section, means including piping for connecting each group of filtering bags to said hollow spokes, means for automatically opening and closing communication between the said 15 chambers and hollow spokes, at predetermined times, comprising valves arranged on opposite sides of the spokes, having extended stems which terminate in bell crank arms, and pins adjustably secured in the path of 20 the bell crank arms.
14. In a revoluble filter, the combination with a wheel comprising a shaft, having independent axial passages terminating in chambers which are separated by a partition, said 25 passages connecting respectively with a vacuum tank, and a source of fluid under pressure, hollow spokes communicating with said chambers, and a narrow rim, of felly blocks secured to said rim, of a wide rim on said 30 felly blocks, extending on opposite sides of said wheel, a circular row of filtering bags secured at one end to said wide rim on opposite 35 sides of the wheel's circumferential center,
13. In a revoluble filter, the combination with a wheel, comprising a shaft having independent axial passages terminating in chambers which are separated by a partition, 5 said passages connecting respectively with a vacuum tank, and a source of fluid under pressure, said wheel having hollow spokes provided with a rim; felly blocks secured to spokes, a circumferential row of flat independent rim sections secured to said rim blocks, and extending laterally across said rim blocks and beyond them far enough to support on opposite sides of said wheel a circumferential row of filtering bags, said filtering 10 bags being arranged in groups on each rim section, means including piping for connecting each group of filtering bags to said hollow spokes, means for automatically opening and closing communication between the said 15 chambers and hollow spokes, at predetermined times, comprising valves arranged on opposite sides of the spokes, having extended stems which terminate in bell crank arms, and pins adjustably secured in the path of 20 the bell crank arms.
15. A revoluble filter, comprising a solution tank, a wheel mounted in said tank so as to be partially submerged, and having hollow spokes; a two-part shaft, the inner ends of 25 which terminate in flanged hub portions which are secured on opposite sides of the wheel, said hubs having chambers which are closed at one end and communicate with axial 30 passages in their respective shaft sections; a plurality of supports arranged around said 35 wheel; groups of filters attached to said supports, each group being in communication with one of said hollow spokes; a pipe in the end of one of said shaft sections, leading to a 40 vacuum tank, a pipe in the end of the other shaft section leading to a source of fluid under 45 pressure, and automatically operated valves for controlling the communication between 50 said spokes and shaft sections.
- In testimony whereof I affix my signature in presence of two witnesses.
